UNITED STATES PATENT OFFICE.

ADOLPH PETZOLD, OF PHILADELPHIA, PENNSYLVANIA, ASSIGNOR TO JOHN H. BROMLEY, JOSEPH H. BROMLEY, AND EDWARD BROMLEY.

DESIGN FOR A TABLE-COVER.

SPECIFICATION forming part of Design No. 22,650, dated August 1, 1893.

Application filed June 2, 1893. Serial No. 476,400. Term of patent 3½ years.

To all whom it may concern:

Be it known that I, ADOLPH PETZOLD, a citizen of the United States, residing in the city of Philadelphia, State of Pennsylvania, have invented and produced a certain new and original Design for a Table-Cover, of which the following is a full, clear, and exact description, reference being had to the accompanying drawing, forming a part of this specification.

My invention relates to the surface ornamentation of a table cover, and consists of the floral and leaf-like border A of sufficient depth at the corners to constitute a practically circular field center, within which is contained a wreath of roses and leaves surrounding two kittens, and partly extending over the same.

I claim—

1. The design for a table cover substantially as shown and set forth. 20
2. The design for the field center consisting of the wreath of roses and leaves and the kittens surrounded thereby; substantially as shown and set forth.

In testimony whereof I have hereunto affixed my signature this 27th day of May, A. D. 1893.

ADOLPH PETZOLD.
